UNITED STATES PATENT OFFICE.

CYRUS GRIM, OF CHICAGO, ILLINOIS, ASSIGNOR TO O. W. RICHARDSON & CO., OF CHICAGO, ILLINOIS.

PRESSER FOOT FOR SEWING MACHINES.

1,411,344.

Specification of Letters Patent.

Patented Apr. 4, 1922.

Application filed October 4, 1920. Serial No. 414,891.

To all whom it may concern:

Be it known that I, CYRUS GRIM, a citizen of the United States, residing at Chicago, in the county of Cook and State of Illinois, have invented a certain new and useful Improvement in Presser Feet for Sewing Machines, of which the following is a specification.

This invention relates to a presser foot for sewing machines and has for one object to produce a presser foot which is adaptable for use with thick heavy rugs or carpets which have a long nap, for example, high pile chenille carpets. Other objects will appear throughout the specifications and drawings from time to time.

The invention is illustrated more or less diagrammatically in the accompanying drawings, wherein;

20 Figure 1 is a plan view with parts in section.

Figure 2 is a side elevation of the same with parts in section.

25 Figure 3 is a side elevation of the presser foot taken from a side opposite to that shown in Figure 2.

Figure 4 is a vertical section on line 4, 4 of Fig. 2.

30 Figure 5 is a plan view of a modified presser foot.

Figure 6 is a side elevation of the same.

Figure 7 is a side elevation of the opposite side of the presser foot.

35 Figure 8 is a vertical section on line 8, 8 of Fig. 5.

Like parts are indicated by like characters throughout.

A is the base on the frame of a carpet upon which an upper surface of chenille A' 40 is fastened by means of a plurality of warp threads A² A³ which engage the chenille of the carpet frame for the purpose of securing the ends of these threads when a portion of the carpet has been cut off. They 45 are arranged substantially parallel to each other as shown in Fig. 1, and are then stitched firmly to the upper surface of the carpet frame by means of cross stitching A⁴. In order to do such sewing on a sewing machine a special form of presser foot is necessary and it is the form of the presser foot to which this invention relates. A 50 presser foot to be used for such purposes must press aside and to some extent press 55 down the chenille surface of the rug dur-

ing the sewing operation. This is necessary in order that the cross stitching will be brought closely up against the edge of the chenille at the end of the carpet.

In the finishing of such carpets it is desirable after the threads have been secured in the manner illustrated in Figure 1, to add a binding over the edge of the carpet to improve the appearance of the edge. It is also desirable to do this by machine, and for this 65 the presser foot illustrated in Figures 5 to 8 inclusive is adapted although either of the forms shown could be used for either purpose.

B is a presser foot having an upwardly 70 extending supporting shank B' which is desirable to be secured in any suitable manner to the sewing machine. B² is the front end of the presser foot and is curved as shown to intercept and bend or press 75 aside the nap of the rug as illustrated in Figure 1. B³ is a perforation in the presser foot through which the needle or needles of the sewing machine may penetrate. It will be understood that this feature of the 80 presser foot is capable of great variation as the presser foot is adaptable to many different types of sewing machines. B⁴ is a lateral extension on the presser foot adapted to press down the nap of the rug in the 85 manner shown in Figures 1 and 8. The form of presser foot shown in Figures 5 to 8 inclusive is adapted for a machine which has a plurality of needles and it differs in a number of respects from the presser 90 foot shown in Figures 1 to 4 inclusive. Each of the forms is designed, however, to manipulate the nap of the carpet so as to permit the sewing close up against the chenille or nap. This is done by first pressing 95 aside and then bending down the nap by contact with the parts of the presser foot.

Referring now particularly to Figure 2, C represents a part of a sewing machine in which the needle C' is mounted for vertical 100 reciprocation. D is the work table of the sewing machine upon which the carpet is placed and across which it is moved during the sewing operation. E is the set plate by means of which the work is moved along 105 through the machine and under the needle. The mechanism for doing this is well known in the art and forms no part of the invention and is therefore not shown or described in detail.

In the form shown in Figs. 5 to 8, inclusive the presser is similar to the form shown in the first four figures except that it is formed to permit sewing of different 5 stitching and when so desired with a plurality of needles. The presser foot rests flat upon the cloth as shown in Fig. 6 in the same manner as does the other form of presser foot shown in Fig. 2. When so positioned the front of the presser foot B² is curved laterally across and serves to straighten up the nap in exactly the same manner as is shown in Fig. 1. Instead of having a projecting wing as is shown in the 10 first form, the body of the presser foot is under cut with the entire upper side portion of the pressure foot overhanging its lower margin. When it moves with relation to the nap, the overhanging portion of the presser foot depresses and bends aside and down the nap in exactly the same manner as the overhanging wing shown in the first form. The additional structural elements appearing in this second form which 15 is apparently differentiated from the first form have no particular function in the pressing function, but are there as above stated to permit of a different manner of sewing and to permit of the use of a plurality of needles.

The use and operation of this device are as follows:

In the carpet to be finished a limited 35 amount of the chenille surface is picked back from the edge. The warp threads which hold the chenille to the carpet frame are then arranged substantially parallel to each other and in this condition the carpet is ready to be finished. It is put into the sewing 40 machine in which one form of the presser foot is mounted and is then run through the machine and sewed in the manner illustrated in Figure 1. During this operation, some of the frame of the carpet from which 45 the chenille has been removed may also be cut off so as to narrow the uncovered portion of the carpet. This may or may not be done during the sewing operation. As the carpet moves through the machine the chenille is 50 contacted by the front of the presser foot which pushes it aside nearest the chenille base over the lateral extension of the presser foot and is forced aside and bent downward. At this point the sewing takes place, and 55 by reason of the displacement of the chenille

it is possible to sew directly up against the chenille. When this sewing operation has been completed the carpet edge is secured from raveling but it is somewhat unsightly. The carpet is therefore subsequently run 60 through a machine which is adapted to produce upon the edge of the carpet a binding which will overlap the uncovered portion of the carpet and the stitching which has just been put upon it. Thus the stitching is concealed and the binding comes directly up against the chenille and furnishes an attractive and workmanlike edge to the carpet. For this purpose it is necessary, as before, 65 that the chenille be pushed aside and down. 70

The two forms of the device shown differ only in that they are adaptable for different types of machines. The form illustrated in Figures 1 to 4 is adapted to a single needle machine and the form illustrated in Figures 5 to 8 is adapted to a machine having a plurality of needles. Of course many such changes might be made to adapt the presser foot to various types of 75 needles and sewing mechanisms.

Although I have shown in my invention an operative mechanism still it is obvious that many changes both of form, size and arrangement of parts might be made without departing from the spirit of my invention and I wish therefore that it be taken 80 as in a sense diagrammatical.

I claim:

1. In a pressure foot for a sewing machine adapted for use with fabric having a long nap, a main pressure foot body, a curved forward projection adapted to contact and to straighten up the nap, a lateral extension in rear of said projection, said extension adapted to contact and to press said nap aside and down.

2. In a pressure foot for a sewing machine adapted for use with fabric having a long nap, a main pressure foot body, a curved forward projection adapted to contact and to straighten up the nap, a lateral extension in rear of said projection, said extension adapted to contact and to press said nap aside and down, said forward projection curved laterally away from said rearward extension.

Signed at Chicago, county of Cook, and State of Illinois, this 30th day of Sept., 1920.

CYRUS GRIM.
